INDIANA.

BOILER STAY-BOLT.

1,273,563.

Specification of Letters Patent. Patented July 23, 1918.

Application filed June 19, 1916. Serial No. 104,587.

To all whom it may concern:

Be it known that we, JOHN A. WOLMER, EDWARD F. HANLON, and GUY L. THOMSON, citizens of the United States, residing at Indianapolis, in the county of Marion and State of Indiana, have invented a new and useful Boiler Stay-Bolt, of which the following is a specification, reference being had to the accompanying drawings, and to the letters and figures of reference marked thereon.

This invention relates to boilers in which steam is to be generated and has reference more particularly to such portions of boilers as have oppositely arranged metallic sheets, as in fire-box structures the invention having reference more particularly to means whereby oppositely arranged sheets of the boilers are stayed or braced.

An object of the invention is to provide an improved boiler stay-bolt that shall be adapted to be welded to and become practically integral with one of two oppositely arranged metallic sheets, more particularly the fire-box sheet, and have its maximum strength at the inside of the fire-box sheet between the two sheets, an aim being to avoid weakening the fire-box sheet by leaving bolt holes therein which hitherto has been a source of trouble and danger because of the development of cracks in the fire-box sheet at the numerous holes into which the stay-bolts have been hitherto screwed.

Another object is to provide an improved stay-bolt that shall be threadless where connected to the fire-box sheet and therefore not be liable to fracture adjacent to the sheet as is the tendency of screw-threaded bolts hitherto used, an aim being to reduce the surface of the stay-bolt that is exposed to water adjacent to the fire-box sheet in order to lessen the accumulation of scale-forming deposits.

A further object is to provide improved means for staying or bracing fire-box sheets so that deteriorating leakage of water shall be prevented and the great expense entailed by the renewal of stay-bolts obviated, to the

end that increased efficiency, durability and economy shall be attained in maintenance and operation.

With the above-mentioned and other objects in view, the invention consists in an improved stay-bolt having a threadless engagement portion adapted to be welded in one boiler sheet and having also another engagement portion adapted to be connected to an oppositely arranged sheet; the invention including also a novel sheet and stay-bolt structure. The invention consists also further in the novel parts and combinations and arrangements of parts as hereinafter particularly described and further pointed out in the appended claims.

Referring to the drawings,—Figure 1 is a side view of the improved stay-bolt as preferably constructed; Fig. 2 represents one end of the stay-bolt; Fig. 3 represents the opposite end of the stay-bolt; Fig. 4 is a longitudinal central section of the preferred form of stay-bolt; Fig. 5 is a fragmentary sectional elevation of boiler sheets and the improved stay-bolts connected therewith; Fig. 6 is a side view of a modified form of stay-bolt; Fig. 7 is a side view of another modified form of stay-bolt that is adapted to be non-rigidly connected to the shell or outer sheet of a boiler; Fig. 8 is an end view of the stay-bolt shown in the preceding Fig. 8; Fig. 9 is a fragmentary sectional elevation of the boiler sheets and the modified stay-bolts shown in Fig. 7 partially connected therewith, and Fig. 10 is a fragmentary sectional elevation of the boiler sheets to which the stay-bolt shown in the preceding Fig. 9 is completely connected.

Like reference characters on the various figures of the drawings indicate corresponding elements or features of construction herein referred to.

In the construction of a fire-box and some portions of boilers an outer sheet or shell 1 is commonly comprised in the structure and has a suitable number of holes 2 in which are screw threads 3, there being an oppositely arranged inner or fire-box sheet 4. For the purpose of the present invention the

inner sheet 4 is provided with plain or threadless holes 5 which are tapering so as to have an inclined or concave face 6, the smaller end or orifice of each hole being at the inside 5 of the sheet or that side which is the nearer to the shell or outer sheet.

The preferred form of stay-bolt comprises an engagement portion 7 having screw threads 8 thereon to be engaged with the 10 screw threads 3, and a body portion 9 extending from the engagement portion, the body portion being cylindrical and plain or devoid of screw threads. The body portion has a tapering engagement portion 10 thereon which has an approximately flat end 11. The body portion 9 preferably is 15 slightly greater in diameter than the hole and the tapering portion is sufficiently long to extend through the hole a sufficient 20 distance to permit of its being upset into the hole without necessitating cutting off operations. The opposite end of the engagement portion 7 has a squared portion 12 25 be engaged by a wrench when applying bolt, and preferably the engagement portion 7 has a leakage channel 13 therein when a tell-tale stay-bolt is desired. When the engagement portion 10 is permanently connected to the sheet 4 it forms or constitutes 30 a substantially homogeneous portion 14 that is substantially integral with the sheet 4, as illustrated in Fig. 5, the body portion 9' being substantially integral with the inside of the sheet.

In some cases when there is a frame or a pad on the outside of the sheet 1 the stay-bolt must be first inserted in the fire-box sheet 4 and thence into the outer sheet 1, in which case the stay-bolt has an engagement portion 15 provided with the screw 35 threads 8 and the body portion 16 that is cylindrical throughout and of suitable diameter to closely fit in a hole 5. The threaded portion is screwed into the hole 3, being 40 tightly fitted to the hole as usual. The body portion extends through the hole 5 when first placed in position and has a squared end portion 17 to be engaged by a wrench. The surplusage of metal is subsequently cut 45 off in the fire-box and after the bolt is permanently connected to the fire-box sheet 4 it forms or comprises a substantially homogeneous or integral portion 18 with the fire-box sheet, the body portion 16' being practically integral with the inside of the sheet.

When it is desired that the stay-bolts have a ball-and-socket connection with the shell or outer sheet of the boiler the stay-bolt comprises a cylindrical body portion 60 19 having a ball-shaped engagement portion 20 on one end and a tapering engagement portion 21 on its opposite end, the latter having an approximately flat end 22. The body portion 19 is of suitable diameter to

closely fit into the hole 5 to permit the engagement portion 20 to be properly connected with the outer sheet. The engagement portion 21 when permanently connected to the fire-box sheet 4, forms or comprises a substantially homogeneous portion 23 practically integral with the fire-box sheet. This type of stay-bolt extends through a bushing 24 which has screw threads 25 that engage the screw threads 3, each bushing being inserted in a hole 2. 70 The engagement portion 20 is seated in the outer end of the bushing and usually is covered by a cap 26 that is removably screwed onto the bushing.

After each stay-bolt is connected to the 80 outer sheet or shell 1 of the boiler structure, the end of the stay-bolt in the fire-box may be cut off if unnecessarily long. A blow-flame, which may be obtained from acetylene gas, is directed into the concave hole 85 and about the engagement portion of the stay-bolt, and thus the inside portion of the fire-box sheet where the bolt hole closely receives the metal of the stay-bolt is first heated, after which the end portion of the 90 stay-bolt and the adjacent portions of the sheet are brought to a welding heat. In some cases the space around the engagement portion within the concave hole is filled or partially filled with metal which is heated 95 and fused with the metal of the bolt and the sheet; or, the metal of the bolt may be upset while heated to fill the hole while the mass is welded together. When the squared portion 12 is cut off from the engagement 100 portion 7 the engagement portion is preferably upset so as to form a steam-tight engagement portion 7', as is customary.

It will be apparent from the foregoing that the inner or fire-box sheet that is exposed to intense heat has practically integral stay-bolts thereon, and therefore the leakage of water into the fire-box space cannot occur and there is no tendency of the sheet to crack, there being no holes in the 110 sheet from which cracks might develop. The life of the fire-box sheet is therefore materially lengthened as compared with the life of a perforated sheet.

Having thus described the invention, what 115 is claimed as new is—

1. A stay-bolt comprising a cylindrical body portion having a plain threadless tapered engagement portion adjacent to one end thereof, a threaded engagement portion 120 on the opposite end of the body portion, and a squared end portion adjacent to the threaded engagement portion.

2. In a boiler-stay structure, the combination with an outer boiler sheet having screw-threaded holes therein, of an inner boiler sheet, and stay-bolts integrally connected to the inner boiler sheet, the stay-bolts extend-

ing through the screw-threaded holes and being connected to the outer sheet by means of the screw threads in the holes.

3. In a boiler-stay structure, the combination with an outer boiler sheet having screw-threaded holes therein, of an inner or fire-box sheet arranged opposite to the outer sheet and having tapered holes therein, the larger ends of the holes being the farther from the outer sheet, and stay-bolts having threadless engagement portions extending into and through the tapered holes to be jointlessly

secured therein to the inner or fire-box sheet, the stay-bolts extending through the screw-threaded holes that are in the outer sheet. 15

In testimony whereof, we affix our signatures in presence of two witnesses.
